UNITED STATES PATENT OFFICE.

WILLIAM HENRY CRAWFORD, OF CLIFTONFORGE, VIRGINIA.

COMBINED CIGAR CUTTER AND LIGHTER.

No. 809,782.

Specification of Letters Patent.

Patented Jan. 9, 1906

Application filed May 11, 1905. Serial No. 259,983.

To all whom it may concern:

Be it known that I, WILLIAM HENRY CRAWFORD, a citizen of the United States, and a resident of Cliftonforge, in the county of Alleghany and State of Virginia, have invented a new and useful Improvement in a Combined Cigar Cutter and Lighter, of which the following is a specification.

My invention is an improvement in combined cigar cutters and lighters; and it consists in certain novel constructions and combinations of parts, as will be hereinafter described and claimed.

In the drawings forming a part hereof, Figure 1 is a vertical longitudinal section of my invention. Fig. 2 is a vertical transverse section of the same.

In the practical application of my invention I provide a box A, of suitable size and shape, within which is contained the mechanism for operating the cutter and lighter. A hollow support B, of conducting material, as brass, is pivotally mounted in a slot a in the upper face of the box A on trunnions b, journaled beneath the slot, and is provided at its upper end with a burner b', fed through a wick b² from a pyramidal reservoir b³, containing gasolene or other liquid fuel, attached to the lower end of the support, the front of the support being carried upward to form an electric contact-point b⁴. A column C, of brass or other conducting material, supported in an insulating-ring c in the box-top, has an arched portion c' extending above the support B and provided with a pivoted contact-point c², retained yieldingly in place by a plate-spring c³, and on the opposite face of the end of the column is an insulating-hood c⁴, of hard rubber or other suitable material, for restraining the backward motion of the support and extinguishing the light. A battery-cell D of ordinary construction is arranged within the box, at the rear thereof, and a wire d connects one of the poles of the cell to the lower end of the column C, while a second wire d² connects the other pole with one of the terminals of a spark-coil E. A third wire e connects the other terminal of the coil with the support B, thus forming an open circuit, with the terminal points b⁴ and c² in juxtaposition. When the support B is swung forward upon its pivot, the contact-points b⁴ and c² brush by each other, making and breaking the circuit, and the spark

formed by the break ignites the gasolene in a well-known manner.

The cigar-cutter is arranged in front and to one side of the lighter and comprises a plate F, sliding in the grooves of slide-bars f, attached to the under surface of the box-top and provided with a rectangular opening f', normally registering with a beveled opening a' in the box-top and having one of the ends f² of the rectangle formed with a cutting edge for coacting with the beveled edge of the opening. A connecting-rod f³, hinged to a depending crank-arm b⁵, rigid with one of the trunnions b, and hinged to the cutter-blade F, imparts motion to the support when the cutter-blade is actuated. A rock-shaft G, journaled in bearings g on the end of the box adjacent the opening, is provided with a rearwardly-extending arm g', having an upward extension g², carrying a plate g³, arranged below the opening a' and adapted to be depressed by the cigar end to rock the shaft in its bearings. A spring H is secured at one end to a shaft h, journaled in bearings h' on the end of the box adjacent the cigar-cutter, and at its other end to a casing h², attached to the wheel h³ on the shaft h, provided with teeth h⁴ on its circumference. The teeth of the wheel mesh with the teeth of a pinion h⁵ on a counter-shaft h⁶, journaled in bearings h', arranged above the shaft h and normally restrained from turning by an arm h⁸ engaging a trip g⁴, rigid with and depending from the rock-shaft G. When the plate g³ is depressed by the cigar-tip, the stop g⁴ is elevated, releasing the arm h⁸, which in its revolution strikes a depending arm f⁴ on the cutter-blade F and forces the blade to the rear, clipping the end from the cigar and through the connecting-rod f³ rocks the support B forward, igniting the wick.

It is necessary that the lighted wick be held in its forward position for a few seconds and be then released, and to attain the former object I provide a catch I, pivoted to the reservoir b³, adapted to snap over the cross-bar of the support i when the said reservoir is tilted forward. To release the catch, I provide a spring K, secured at one end to a shaft k, mounted in bearings k' on the side of the box, and at its other end to a casing k², attached to a wheel on the shaft k. Teeth k⁴ in the periphery of the wheel mesh with the teeth of a pinion k⁵ on a shaft k⁶, mounted in

front of the shaft k in bearings k^8 on the sides of the box-top. The shaft k^6 is normally restrained from rotation by the engagement of a catch k^9 on a roller k^{10} on the shaft k^6 with 5 one arm of a rock-shaft k^{11} , journaled in bearings k^{12} on the under face of the box-top. A second arm k^{13} on the rock-shaft k^{11} extends into the path of the arm h^8 on the shaft h^6 , before mentioned, and the shaft k^{11} is rocked 10 thereby, thus releasing the catch k^9 and allowing the roller k^{10} to rotate in the direction of the arrow 2. A projection k^{14} on the roller k^{10} strikes the tail of the spring-catch I, releasing the reservoir and allowing the support to tilt back into inoperative position. 15

The gearing of the shafts h , h^6 , k , and k^6 is so proportioned that an interval of approximately fifteen seconds intervenes between the striking of the depending arm f^4 on the 20 cigar-cutter and the releasing of the catch I from the reservoir, thus allowing ample time for the cigar to be lighted. The inner ends of the shafts h and k are extended beyond the bearings h' and k' to openings l l' in the 25 sides of the box and squared to receive a key for winding the springs, and the shaft k^6 is provided with a governor h , of ordinary construction, to regulate the motion thereof.

In operation the cigar-tip is introduced 30 into the opening in the box-top, depressing the plate g^3 and releasing the stop g^4 , thus allowing the spring to rotate the shaft h^6 . The arm h^8 strikes the depending arm f^4 , moving the cutter-blade to the rear and 35 through the connection f^3 tilting forward the support B, igniting the wick and presenting the flame in position for lighting the cigar. The support is retained in its forward position until the continued rotation of the shaft 40 h^6 brings the arm h^8 into contact with the forwardly-extending arm of the rock-shaft k^{11} , thus rocking the shaft and releasing the catch k^9 . The rotation of the roller k^{10} brings the projection k^{14} into contact with the tail of the 45 catch I and releases the reservoir, allowing the burner to tilt back under the hood c^4 .

It will be evident from the description that my device is entirely automatic in its operation, performing its cycle of movements in 50 proper sequence and always returning the burner into position under the extinguishing-hood, thus preventing waste of fuel from failure to extinguish the flame.

I do not choose to limit myself to the particular form of burner described, since it is 55 obvious that any form of fluid-burner will serve equally well, nor to the shape of the reservoir, since the spring-catch might engage directly with the support instead of with 60 the reservoir.

It is sometimes desirable to ignite the burner without clipping the cigar, and for this purpose I provide the pin M, connected with

the rock-shaft G and extending upward through the box-top in front of the opening 65 for the cigar end.

Having thus described my invention, what I claim as new, and desire to secure by Letters Patent, is—

1. In a combined cigar cutter and lighter, 70 the combination of a box provided with a slot, a burner-support pivotally mounted in the slot and provided with a reservoir at its lower end within the box, a burner on the support, a contact-point adjacent to the support, a contact-point supported above and in front of the first-named contact-point, an extinguisher supported above the burner, an electrical battery, a spark-coil, an electrical connection between the contact-points and 75 including the battery and spark-coil, a cutter-plate for cutting cigar ends, slidably mounted on the lower face of the box-top beneath an opening therein adapted to receive the end of the cigar, a connection between 80 the cutter-plate and the burner-support whereby the reciprocation of the latter will vibrate the former, a spring-actuated lug, means for restraining the movement of the lug, means whereby said restraining means 85 may be released by the end of the cigar, means on the cutter-plate engaged by the lug, to move the plate rearwardly, and tilt the burner-support forwardly, means engaging the lower end of the burner-support to hold 90 the parts in such position a spring-actuated lug for releasing said holding means, means for restraining the movement of the lug, and means whereby the first-named lug may release said restraining means. 100

2. In a combined cigar cutter and lighter, the combination of a burner, a swinging support for the burner, means for feeding the burner with fluid, means for igniting the burner comprising a contact-point on the 105 burner, a contact-point adjacent thereto, and in the path of travel of the contact-point on the burner, an open electrical circuit including a battery and a spark-coil, and closed by the conjunction of the contact-points, a cigar-end-cutter plate slidably mounted beneath an opening in the box-top for receiving the end of the cigar to be cut, a connection between the cutter-plate and the swinging support, whereby the rearward movement of the 110 cutter-plate swings the support forward, means for moving the cutter-plate rearwardly, means for restraining said moving means, means whereby the cigar end in the opening in the box-top, may release said restraining means, means for holding the cutter-plate in its rearward position, moving means for releasing the holding means, 115 means for restraining the movement of the releasing means, means whereby the cutter-plate-moving means may release the restrain- 120 125

ing means, whereby the parts return to their normal position, and means for extinguishing the burner.

3. In a combined cigar cutter and lighter, the combination of the box, a swinging support pivotally mounted in the box-top, a burner on the support, means for igniting and extinguishing the burner operated by the movement of the support, a cutter-plate for clipping the ends of cigars movably mounted beneath an opening in the box-top, means whereby the rearward movement of the cutter-plate may swing the support forwardly, means to move the cutter-plate rearwardly, means to restrain the cutter-plate-moving means, means whereby the cigar end may release the restraining means, means for holding the cutter-plate in its rearward position, moving means for releasing the holding means, means for restraining the movement of the releasing means, and means whereby the cutter-plate-moving means may release the restraining means.

4. In a combined cigar cutter and lighter, the combination of a casing, a swinging support mounted in the top of the casing, and provided with a burner, means for igniting and extinguishing the burner operated by the movement of the support, a cutter-plate for coöperating with an opening in the casing, to clip the ends of cigars inserted through the opening, a connection between the cutter-plate and the swinging support, whereby movement of the former imparts motion to the latter, means to move the plate rearwardly, means to restrain the moving means, means whereby the cigar end may release the restraining means, means to hold the cutter-plate in its rearward position, moving means to release the holding means, means to restrain the releasing means, and means whereby the cutter-plate-actuating means may release the restraining means.

5. In a combined cigar cutter and lighter, the combination of a casing, a swinging support mounted in the top of the casing and provided with a burner, means for igniting and extinguishing the burner, operated by the movement of the swinging support, a cutter-plate coöperating with an opening in the casing to clip the ends of cigars inserted through the opening, means for actuating the swinging support from the movement of the cutter-plate, normally inactive means for moving the cutter-plate rearwardly, means whereby the cigar end may actuate the cutter-plate-moving means, means for holding the cutter-plate in its rearward position, means for releasing said holding means, and means whereby the cutter-plate-moving means may actuate the releasing means.

6. In a combined cigar cutter and lighter the combination of a casing, a swinging support mounted in the top of the casing and

provided with a burner, means for igniting and extinguishing the burner operated by the swinging of the support, a cutter-plate coöperating with an opening in the casing to clip the end of a cigar inserted through the opening, means for actuating the swinging support synchronously with the cutter-plate, normally inactive means for moving the cutter-plate in one direction, means whereby the cigar end may actuate the cutter-plate-moving means, means for holding the cutter-plate at the end of its movement, normally inactive means for releasing the holding means, and means whereby the cutter-plate-moving means may actuate the releasing means.

7. In a combined cigar cutter, and lighter, the combination of a swinging support provided with a burner, means for igniting and extinguishing the burner operated by the swinging of the support, a cigar-cutter for clipping the end of a cigar inserted in the cutter, means for actuating the cutter and for swinging the support forwardly, means for holding the support in its forward position, moving means for actuating the cutter and swinging the support and subsequently releasing the holding means, and means whereby said moving means, may be actuated by the insertion of the cigar end into the cutter.

8. In a combined cigar cutter and lighter, the combination of a swinging support, provided with a burner, a cigar-cutter for clipping the end of a cigar inserted in the cutter, a single means for actuating the cutter and for swinging the support in one direction, means for holding the support from swinging in the opposite direction, means for releasing the holding means, and means whereby the insertion of the cigar end into the cutter may actuate the cutter-actuating means, and the releasing means.

9. In a combined cigar cutter and lighter, the combination of a swinging support provided with a burner, means whereby the burner is ignited and extinguished by the swinging of the support, a cigar-cutter for clipping the ends of cigars inserted in the cutter, means for synchronously actuating the cutter and swinging the support, and means whereby said means may be actuated by the insertion of the cigar end into the cutter.

10. In a combined cigar cutter and lighter, the combination of a support provided with a burner, a cigar-cutter for clipping the ends of cigars inserted into the cutter, means acting in sequence for actuating the cutter and igniting and extinguishing the burner, and means whereby the insertion of the cigar end into the cutter may actuate the said means.

11. In a combined cigar cutter and lighter the combination of a burner, means whereby to clip the end of a cigar, means whereby to ignite the burner, means to extinguish the burner, means actuating each of the said

means in the order named, and means whereby the end of the cigar may actuate the said actuating means.

12. In a combined cigar cutter and lighter, the combination of a burner, a cigar-cutter for clipping the end of a cigar inserted into the cutter, means for igniting and extinguishing the burner, means whereby the insertion of the cigar end into the cutter may actuate the igniting and extinguishing means.

13. In a combined cigar cutter and lighter the combination of a swinging support, provided with a burner, means whereby the

swinging of the support in one direction ignites the burner, means whereby the swinging of the support in the opposite direction extinguishes the burner, a cigar-cutter for clipping the end of a cigar inserted in the cutter, means for actuating the cutter and swinging the support, and means whereby the insertion of the cigar end into the cutter may actuate the last-named means.

WILLIAM HENRY CRAWFORD.
